UNITED STATES PATENT OFFICE

110,442

DESIGN FOR A CASE FOR OPHTHALMIC MOUNTINGS

Arthur J. Pratt, Southbridge, Mass., assignor to American Optical Company, Southbridge, Mass., a voluntary association of Massachusetts

Application March 28, 1938, Serial No. 76,123

Term of patent 14 years

To all whom it may concern:

Be it known that I, Arthur J. Pratt, a citizen of the United States, residing at Southbridge, in the county of Worcester and State of Massachusetts, have invented a new, original, and ornamental Design for a Case for Ophthalmic Mountings, of which the following is a specification, reference being made to the accompanying drawing, forming a part thereof.

Fig. I is a perspective view of a case for ophthalmic mountings embodying my design; and

Fig. II is an end view of the case shown in Fig. I.

The characteristic features of my design comprise broadly the deep cup shape and proportion of the main body portions of the case and relatively narrow cupped cover portions. The contour of said portions are curved and blended with each other at their meeting edges to provide a smooth contour surface.

I claim:

The ornamental design for a case for ophthalmic mountings substantially as shown and described.

ARTHUR J. PRATT.
